DOOR HANGER

Filed May 22, 1928

Inventor

C. E. Bell

By Clarence A. O'Brien
Attorney

UNITED STATES PATENT OFFICE

CHARLES E. BELL, OF BUCKLIN, KANSAS

DOOR HANGER

Application filed May 22, 1928. Serial No. 279,724.

The present invention relates to improvements in door hangers, and has reference more particularly to a means for lubricating the bearings and the axle on the ends of 5 which are secured the track engaging rollers.

One of the important objects of the present invention is to provide a door hanger wherein the housing is formed at its outer side with an opening adapted for communication with 10 the open end of the hollow axle, whereby the lubricant can be supplied to the hollow axle without necessitating the removal or disassembly of the traveling carriage of the door hanger from its support.

Still a further object of the invention is to 15 provide a door hanger of the above mentioned character which is simple in construction, inexpensive, strong and durable and further well adapted to the purpose for which 20 it is designed.

Other objects and advantages of the invention will become apparent from the following description when taken in connection with the accompanying drawing.

In the accompanying drawing wherein like reference characters indicate corresponding parts throughout the same,

Figure 1 is a vertical sectional view through the door hanger embodying my invention.

Figure 2 is a sectional view taken approximately on the line 2—2 of Figure 1, and

Figure 3 is a detail showing the axle with one of the rollers secured on one end thereof, the other end portion of the axle being 35 shown in section.

In the drawing wherein for the purpose of illustration is shown the preferred embodiment of my invention, the numeral 1 designates generally the housing the same comprising a wall engaging plate 2 that is secured to a vertical wall in any appropriate manner. The lower edge of this plate is disposed laterally to provide an inner track 3. The housing also includes an outer metallic

40 plate section 4 that is secured along its upper edge to the outer face of the upper edge portion of the plate 2, the intermediate portion of this outer plate being inclined downwardly and outwardly as at 5, and a slightly 45 curved vertically disposed wall 6 extends

downwardly from the inclined portion 5. The lower edge portion of this outer plate 4 is disposed inwardly toward the plate 2 to provide an outer horizontal track 7, and the inner edge of this track is spaced with respect to the free edge of the inner track 3. A depending shield 8 is provided at the inner edge of the track 7, as clearly indicated in Figure 1.

The vertical wall 6 of the outer section of the housing 1 is formed at spaced intervals with openings such as is shown at 9, and the purpose thereof will be hereinafter more fully described.

A cylindrical hub 10 is arranged within the housing, and a bolt 11 is threaded into the bottom of the central portion of the hub, the bolt extending downwardly between the inner opposed edges of the tracks 3 and 7, and having connected at its lower end the door supporting unit 12. As this unit forms no important part of the present invention, a detailed description thereof is thought unnecessary.

This hub is formed with a longitudinal bore 13 through which is disposed the elongated axle 14, said axle being formed in its intermediate portion with an oil outlet slot 15, and this slot has communication with the inner end of the oil passage formed longitudinally in one end of the axle, said passage being designated by the numeral 16, and in Figure 3, there is shown in detail this oil passage. The ends of the axle project beyond the 85 respective ends of the hub and have secured thereon, the flanged rollers or wheels 17 and 18, respectively, the flanges of these wheels being disposed inwardly and encircling the respective ends of the hub as clearly shown in 90 Figure 1. The flanged roller or wheel 17 is adapted to travel along the upper face of the track 3, while the other roller or wheel travels along the track 7.

The axle 14 may be secured to the respective rollers or wheels in any appropriate manner whereby said elements will rotate in unison, and in the present instance, I have shown the ends of the axle as being threaded for engagement within threaded openings 100

formed in the central portion of the respective rollers.

Suitable roller bearings 19 are arranged with the bore 13 of the hub 10 for cooperation with the axle 14. Each end of the hub 10 is formed with a central enlarged socket 20, each socket being threaded. A felt washer 21 is disposed within each socket for disposition around the axle 14, and a nut 22 is threaded in each socket for securing the said washer in proper position in the socket against the inner face thereof as clearly shown in Figure 1.

When the open end of the passage 16 is in communication with the hole 9 formed in the vertical wall 6, the lubricant may be forced into the passage.

The oil or grease delivered to the passage 16 will be forced outwardly through the slot 15 around the intermediate portion of the axle 13 so that the axle and the bearings will be properly lubricated to permit the free movement of the rollers 17 and 18 along the tracks 3 and 7, respectively. The felt washers 21 will maintain the lubricant from escaping beyond the bearing 19 as is readily obvious from the construction shown.

It will thus be seen from the foregoing description that I have provided a door hanger wherein the parts can be readily and easily lubricated whenever necessary, and it will not be necessary to disassemble the parts in order to lubricate the moving elements. The simplicity of my door hanger enables the same to be constructed at a very low cost, and can furthermore be readily and easily assembled or disassembled whenever necessary.

While I have shown the preferred embodiment of my invention it is to be understood that minor changes in the size, shape and arrangement of parts may be resorted to without departing from the spirit of the invention or the scope of the appended claim.

Having thus described the invention, what I claim as new and desire to secure by Letters Patent is:—

In a door hanger, a housing for attachment to a support, a track formed at the bottom of the housing, said track being slotted, the outer vertical walls of the housing being formed with a lubricating opening, a hub arranged within the housing, an axle journaled for rotation within the hub, the ends of the axle extending beyond the ends of the hub, flanged track engaging rollers secured on the ends of the axle for rotation therewith, the flanges being directed inwardly and encircling the respective ends of the hub, a door supporting unit suspended from the hub through the slotted track, said axle being formed at one end with lubricant receiving passage, the intermediate portion of the axle being formed with a lubricant discharge slot to feed the lubricant from the passage to the exterior of the axle, a lubricant

being supplied to the passage when the open outer end thereof is in communication with the opening formed in the outer vertical wall of the housing.

In testimony whereof I affix my signature. 70
CHARLES E. BELL.
